UNITED STATES PATENT OFFICE.

ALPHONS HORTEN, OF BERLIN-WILMERSDORF, GERMANY.

DEVICE FOR THE PRODUCTION OF CONCRETE PIPES AND ESPECIALLY FOR DEVICES
FOR APPLYING THE CONCRETE.

Application filed June 29, 1926, Serial No. 119,500, and in Germany September 24, 1925.

My invention relates to devices for the production of concrete pipes, and especially to devices for applying the concrete, in a finely divided state to the outer side of a slowly rotating, power-driven core or former with the aid of a rigidly rotating centrifugal wheel.

By numerous and exhaustive experiments I have found that, in order to obtain uniform distribution of the concrete on the core or mould, which carries an iron reinforcement, it is necessary to apply the concrete in a very finely divided state and in an extremely uniform manner. In my prior application Serial No. 4015 dated January 7th, 1925, I have described a device suitable for this purpose and exhibiting in particular a feed cylinder which is filled with ready mixed concrete and delivers this uniformly, in a thin continuous length, by the aid of a power-driven piston, to a centrifugal wheel which projects it against the core. My present invention relates to a further development of this feed device, and more particularly to a suitable arrangement of the whole and to details of the centrifugal wheel and feed cylinder.

The invention is illustrated in the drawing, in which—

Fig. 1 represents the entire plant, in a somewhat diagrammatical form, certain parts being shown, for the sake of clearness, on a larger scale than other parts represented in the same figure.

Fig. 2 is a horizontal section along the line II—II of Fig. 1, in partial section and with some of the parts omitted.

Fig. 3 shows a centrifugal wheel, as a side elevation and in partial section, on a larger scale.

Fig. 4 is an elevation of same.

Fig. 5 shows, on a still larger scale, a special form of the device for feeding the concrete, coacting with a single vane of the centrifugal wheel.

Figs. 6 and 7 are representations, corresponding to Figs. 3 and 4 of another form of centrifugal wheel.

The total arrangement will first be described with reference to Fig. 1. 2 is a cylindrical core or former the end 3 of which is thickened to form a flange or socket; 4 is a shaft for this core rotatably supported at

both ends in a suitable manner; 5 is a pinion gear; and 6 is an electromotor that drives the pinions 5 and therefore the shaft 4. The arrangement is such that the electromotor turns the shaft 4 at a low speed when started. It is clear that the pinion gear shown is merely intended to represent a speed-reduction gear, and that, in reality, a train of pinions, worm wheels and the like, may be interposed between the motor and the shaft.

The smooth surface of the core 2 shown can be covered with an iron reinforcement for the pipe to be formed, at a suitable moment in the process of manufacture, as described in my application, Serial No. 89483, so that no further details and description seem to be necessary on the present occasion.

Laterally in relation to the shaft 4, and parallel thereto, are erected guides 7 which, in the example, consist of two round pillars, having one end supported by the floor 8 and the other end bearing against the ceiling 9 of the workshop. 10 is a frame carrying the hereinafter described parts for the centrifugal device and provided on both sides with sliding shoes 11, which fit the guides 7 and are firmly secured to the frame 10 by any known means. Two draft ropes 12 and 13 are attached to the upper side of the frame, preferably in the manner indicated. The rope 12 passes over guide pulleys 14, 15 to a counterweight 16, which balances a large proportion of the weight of the frame and the parts mounted thereon, so that only a very small effort is required for lifting, which is effected by means of the rope 13. The lifting rope 13 passes over a pulley 17 to a two-sheave block tackle 18, the bottom part of which, 19, is connected to the rod 20 of a piston 21 adapted to slide in a cylinder 22. 23 is a pipe which opens into the cylinder 22 above the piston 21; and water under pressure can be admitted through a valve 24, from a pipe 25, to the upper side of the piston, whilst, on the valve 24 being closed, the opening of a second valve 26 enables water to pass from the cylinder into a discharge pipe 28. If the valve 26 be closed and the valve 24 open, so that water under pressure passes into the cylinder 22, the piston 21 descends and draws the rope 13 downward. The pro-

cess is reversed when the valve 24 is closed and the valve 26 open, so that the piston 21 ascends and draws the rope 13 upward. The piston 21 is connected to the shaft 4, so that the rotation of the shaft 4 causes the piston 21 to move up and down, and the movement of the piston 21 causes the rope 13 to move up and down, so that the frame 10 is raised and lowered, and the centrifugal wheel 2 is rotated.

vision of the two-sheave block tackle enables, in the well known manner, a short piston stroke to correspond to an increased or multiplied movement of the end of the 5 rope that is attached to the frame 10.

The valves 24, 26 may be controlled by hand, or may be controlled automatically (by means not shown) in such a manner that the valve 24 is opened and the valve 26 10 closed when the frame 10 and its appurtenances have reached the bottom of the track 7, and that, conversely, the valve 24 is closed and the valve 26 opened when the frame reaches the upper end of its travel. 15 In this way the frame 10 is raised or lowered in relation to the floor 8 and the core 2 in accordance with the admission of the pressure medium and its discharge therefrom. There is no need to explain further 20 that the various operations can be performed at the desired speed by suitably dimensioning or throttling the passages in the valves 24 and 26.

The means for feeding and projecting 25 the concrete on to the core, which means are mounted on the frame 10, will now be described.

Said frame 10 carries two cylinders 29 and 30 mounted in coaxial alignment. The 30 cylinder 29 contains a piston 31, on both sides of which pipes 32, 33 open into the cylinder. These pipes lead to a reversing valve 34 of any suitable kind, by means of which they can be connected, at will, with a pipe 35 admitting water under pressure, or a discharge pipe 36. To simplify the explanation, it is assumed that the pipe 35 leads direct to a force pump 37, connected, by means of a pipe 38, with a tank 39, into 40 which opens the pipe 36. It will be evident that accumulator devices can be provided for the pressure water in known manner, and that the delivery pipe can be provided with throttling devices for controlling the 45 rate of flow of the water in order, in this manner, to enable the pressure on either side of the piston 31 to be regulated at will. The pipe 25 may also be connected with the pump 37, and the pipe 28 led to the 50 tank 39. These connecting pipes have been omitted solely in order to make the drawing clearer.

With the valve 34 in the position shown, 55 the pressure water produced in the pump 37 passes to the left side of the piston 31, and tends to drive it towards the right, whilst the water situated on the right of the piston can run away through the pipe 33, valve 34 and pipe 36. Turning the valve clockwise through 90° causes the pressure water 60 to flow in the opposite direction. It is clear that minor adjustments will also enable the velocity of the piston 31 to be controlled. The rod 40 of the piston 31 is connected to a 65 piston 41 adapted to travel in the second

cylinder 30. The upper side of the cylinder 30 is provided with a feed hopper 42, the bottom of which is preferably fitted with a closing device 43. With the piston 41 in the left hand position shown, mixed concrete can 70 be charged into the cylinder 30 from the hopper 42; and when the cylinder is full, the device 43 can be closed. On the piston 31 of the cylinder 29 being moved towards the 75 right, in the described manner, pressure will be exerted on the concrete in the cylinder 30.

The right head 44 of the cylinder 30 is provided—preferably near the lower edge—with a discharge pipe 45, bent downward at its outer end 46. When the device is actuated in the described manner, the concrete is forced through the pipe 45 and issues at 46 in a uniform thin continuous length and at a uniform speed corresponding to the uniform stroke of the pistons 31 and 41, this 85 uniform stroke being ensured by the described hydraulic actuating device.

A paddle wheel 47, intermittently actuated from the outside, for example by a hand crank 48, or by mechanical agency (not 90 shown), is preferably arranged close against the head 44 of the cylinder 30. This arrangement prevents any of the concrete from lodging and setting in front of the cylinder head and sidewise of the pipe 45 during the 95 working process and necessitating setting the apparatus out of action at intervals.

A centrifugal wheel 50 is mounted, below the opening 46, in bearings 49 attached to the frame 10, which wheel is illustrated in detail, in various embodiments, in Figs. 3-7, and is adapted to be set in rapid rotation about its horizontal axis by means of an 100 electromotor 51. As can be gathered from Fig. 2 this wheel rotates immediately in front 105 of the revolving core 2, and projects the continuous length of concrete issuing from the opening 46 against the surface of the core in a uniformly finely divided condition. Through the rotation of the core on the one hand and the up and down movement of the frame 10 and attached parts on the other, the concrete is uniformly distributed over 110 the entire surface of the core.

The special detail construction of the centrifugal wheel found to be particularly suitable as a result of numerous experiments, will not be considered. Centrifugal wheels which beat against the concrete with flat vanes, have previously been used. When a 115 surface in rapid rotation strikes at right angles against a stationary mass of concrete, the material impinged upon is not projected in a direction tangential to that of the rotation of the wheel, but is scattered as by an explosion, even laterally and towards the interior of the wheel. In this way, the consumption of power and material is very 120 greatly increased; at the same time, a large quantity of dust is produced, and, in ad- 125

dition, uniform application of the concrete is prevented. These drawbacks are obviated by my centrifugal wheel.

In the embodiment according to Figs. 3 and 4 detachable shoes 53 are secured, for example by means of screws 54, on the smooth outer surface of the wheel 50 which is similar to an ordinary belt pulley in shape. These shoes strike, by means of their central parts 55 against the length of concrete issuing from the opening 46. Each shoe is provided on either side of its striking surface, with cheeks 56 which prevent the lateral dispersion of the concrete. Scattering towards the interior of the wheel is prevented by bottom flanges 57 and also by the solid rim of the wheel 50. Radial dispersion in the outward direction is prevented, on the other hand by the concrete itself issuing at 46 (see Fig. 5). The pipe 45 is preferably provided with thickened walls 58, at the mouth 46, as shown in Fig. 5, these walls being machined at 59 in accordance with the radius of the correspondingly shaped shoes 53, only a central aperture 60 being left for the passage of the concrete. In addition, the rear wall 55 of each shoe may be arranged obliquely, as indicated by the dot-and-dash line in Fig. 5 and the middle portion of the shoe may be provided behind the surface 55, with grooves 61, which form a kind of labyrinth packing and prevent the discharge of any concrete in that direction. This arrangement ensures the whole of the concrete being projected in a tangential direction, as indicated by the arrows 62 in Fig. 5 and delivered direct on to the surface of the core.

The shoes 53 can be easily detached by loosening the screws 54, so that worn shoes can be replaced at once, without much difficulty, for instance during the time in ordinary working when a core or form 2 with a finished tube is removed and a fresh one is connected to the shaft 4, so that the regular operation of the machine need not be interrupted for the purpose of replacing.

Figs. 6 and 7 represent a somewhat modified centrifugal wheel, which is formed by shrinking, or pressing by hydraulic power, a solid ring 63 on to the rim of the wheel 50, said ring being provided with punched or milled trapezoidal pockets 64. The narrow sides 55 of these trapezoids act in the same manner as the striker surfaces 55, and the side walls 56 act in the same manner as the surfaces 56 of the shoes 53. In this case, the whole ring 63 is detached and replaced by a new one when worn. This form also is simple and reliable in operation; but the embodiments according to Figs. 3-5 are preferred.

Having now described and illustrated my invention I declare that what I claim is as follows:

1. A device for the production of concrete pipes comprising a substantially cylindrical form, means for rotating the said form, a centrifugal wheel, means for rotating the wheel, means for carrying concrete in a uniformly finely divided condition to the periphery of the said centrifugal wheel, vanes at the periphery of the said wheel, means for rotatably supporting the wheel in the neighborhood of the axis of the said form and means for imparting a reciprocating movement to the said wheel and its cooperating parts in a direction parallel to the axis of the said form. 70

2. A device for the production of concrete pipes comprising a form rotatably supported in such a manner that it may be rotated about its longitudinal axis, means for imparting a rotary movement to the said axis and the form connected thereto, a guide parallel to the axis of the said form, a frame arranged to travel along the said guide up and downwards, means for imparting an up and downward movement to the frame, a horizontally arranged cylinder rigidly connected to the said frame, a piston moving within the said horizontal cylinder, a hopper for filling the cylinder with concrete and arranged near the one end of the said horizontal cylinder in axial alignment with the said first cylinder, a piston in the second cylinder connected to the said first piston, means for admitting fluid under pressure to one or the other side of the said second mentioned piston, means for regulating the fluid admission, a passage at the coverside of the said cylinder opposite the said hopper, a centrifugal wheel rotated before the opening of the said passage, means for supporting the said wheel at the said frame, means for imparting a rotary movement to the wheel. 100

3. A device for the production of concrete pipes comprising a form rotatably supported in such a manner that it may be rotated about its longitudinal axis being arranged in a vertical direction, a frame being arranged to travel along the said guide up and downwards, a lifting rope fixed to the said frame, a two-sheaved block tackle for the said rope, rollers for leading the rope to the said tackle, a cylinder, a piston moving in the said cylinder, and connected to one sheave of the said block tackle, means for admitting fluid under pressure to the one side of the said piston and to remove it respectively regularly. 110

4. A device for the production of concrete pipes comprising a form rotatably supported in such a manner that it may be rotated about its longitudinal axis being arranged in a vertical direction, means for imparting a rotary movement to the said axis and the form connected thereto, a guide parallel to the axis of the said form, a frame being arranged to travel along the said guide up and down- 125

- wards, means for imparting an up and downward movement to the frame, a horizontally arranged cylinder rigidly connected to the said frame, a piston moving within the said horizontal cylinder, a hopper for filling the cylinder with concrete and arranged near the one end of the said horizontal cylinder in axial alignment with the said first cylinder, a horizontally arranged passage at the coverside of the said horizontal cylinder, being arranged below the axis of the cylinder near the periphery of the cylinder and the end of this passage being bent downward to open in a vertical direction, a paddle wheel being arranged near the said cover, and means for imparting a rotary movement to the said paddle wheel.
6. A device for the production of concrete pipes comprising a substantially cylindrical form, a vertically arranged axle supporting the gear for rotating said form, centrifugal wheel, means for rotating the wheel, means for carrying concrete in a uniformly finely divided condition to the said centrifugal wheel, a cylindrical peripheral rim at the centrifugal wheel, easily detachable blades fixed to the said rim, and means for imparting a reciprocating movement to the said wheel parallel to the axis of the said form.
7. A device for the production of concrete pipes comprising a substantially cylindrical form, a vertically arranged axle supporting the gear for rotating the said form, a centrifugal wheel, means for rotating the wheel, means for imparting a reciprocating movement to it in a vertical direction and parallel to the axis of the said form, means for carrying concrete in a regular manner and in a finely divided condition to the said centrifugal wheel and blades at the said wheel acting upon the concrete by means of shoe-shaped surfaces, a peripheral rim at the said rim and means for detachably fixing the said blades at the rim.
- In testimony whereof I have affixed my signature.

ALPHONS HORTEN.
